CABINET FOR CASSETTES OR THE LIKE

William P. McRae, 19969 Acre St.
Northridge, Calif. 91324

Filed Oct. 18, 1973, Ser. No. 407,752

Term of patent 14 years

Int. Cl. D6—04

U.S. Cl. D6—167

Fig. 1

Fig. 2

Fig. 3

Fig. 4

Fig. 6

Fig. 5

FIG. 1 is a front, top and left side perspective view of a cabinet for cassettes or the like showing my new design;
FIG. 2 is a front elevational view;
FIG. 3 is a right side elevational view;
FIG. 4 is a rear elevational view;
FIG. 5 is a bottom plan view; and
FIG. 6 is a view similar to FIG. 1 with the door in open position.

I claim:

The ornamental design for a cabinet for cassettes or the like, substantially as shown and described.
